GRID-CONTROLLED GASEOUS DISCHARGE DEVICE

Paul W. Stutsman, Needham, Mass., assignor to
Raytheon Manufacturing Company, Newton,
Mass., a corporation of Delaware

Application September 1, 1949, Serial No. 113,551

3 Claims. (Cl. 313—250)

1

This application relates to electron discharge devices and more particularly to gaseous discharge devices of the grid control type.

In applicant's copending application, Serial No. 57,533, filed October 30, 1948, there is disclosed a gaseous discharge device of the cold cathode type capable of passing high peak currents on the order of 100 amperes, said discharge device being built in a metal envelope of normal size. It has become desirable to devise a means of producing a tube of this general type in a miniature bulb. Applicant has discovered that the grid and cathode may be firmly and rigidly supported by positioning an insulating member between them and urging this assembly together. By so doing, at least one of the grid support members may be eliminated and a more rugged and accurately positioned device may be produced. This device may then be reduced to a suitable size for insertion into the miniature bulb without detracting from the ruggedness of the construction. This structure taken in conjunction with a shielded anode member will produce a device capable of passing high peak currents. A high forward voltage may be obtained by adjustment of the spacing between the grid and cathode to a distance less than the minimum breakdown distance for the gas and pressure used. A high inverse peak voltage is possible due to the relatively large spacing between the anode and cathode. A short deionizing time is produced by the limited cross section of the discharge path and the large area surrounding said path for collecting ionized gas components.

The means of producing a device having these and other advantages will be apparent to persons skilled in the art as the description thereof progresses, reference being had to the accompanying drawings wherein:

Fig. 1 illustrates a longitudinal cross-sectional view of the device embodying this invention taken along line 1—1 of Fig. 2; and

Figs. 2 and 3 are transverse cross-sectional views of the species shown in Fig. 1 taken along lines 2—2 and 3—3, respectively, of Fig. 1.

Referring now to Fig. 1, there is shown an envelope 10 having a glass button 11 sealing its lower end. The upper end of envelope 10 is closed by a glass seal 12 through which extends a conducting member 13. Attached to conducting member 13 is a metal cap 14 which is rigidly held to member 13, for example, by a quantity of solder 15. The cap 14 is firmly held to the glass sealing member 12 by a mass of glue 16.

The lower end of rod 13 which extends downwardly inside envelope 10 is attached to an anode member 17 comprising a short rod of carbon whose diameter is substantially equal to the diameter of member 13. The attachment of anode member 17 to member 13 is accomplished by a

short metallic sleeve 18 surrounding and frictionally engaging the lower end of conducting member 13 and the upper end of cathode 17.

Surrounding conducting member 13 and anode member 17 is a metallic shield member 19 comprising a cylinder whose lower end extends into envelope 10 for substantially the same distance as carbon button 17 and whose upper end is imbedded in the glass sealing member 12. The sleeve 18 does not touch the sleeve 18, the carbon rod 17, or conducting member 13.

Surrounding the shield member 19 is a dielectric shield 20 comprising a glass tube fused to seal 12 and extending down into envelope 10 for the length of metallic shield 19.

Surrounding the dielectric shield 20 is a tubular grid member 21, which may be, for example, of carbon, whose upper end is in close proximity with but not touching the glass seal 12 and the dielectric shield 20, and whose lower end extends downward into envelope 10 for approximately twice the length of dielectric shield 20. The recess in grid member 21, which accommodates the anode structure and its accompanying shields, extends downward with a uniform diameter from the top thereof to a point somewhat below the end of shield member 20, for example, approximately one diameter of sleeve 18 therebelow. The diameter of the recess is then reduced to a diameter which may be, for example, approximately equal to the inside diameter of shield 20 and extends the remainder of the length of grid member 21. Surrounding grid member 21 is a ceramic member 22 in contacting engagement therewith from a point adjacent the lower end of conducting member 13 downward to the lower end of grid member 21. The ceramic member 22 extends downward beyond the lower end of grid member 21 for a distance approximately equal to the radius of envelope 10. The recess which accommodates grid member 21 is substantially reduced below the lower end of said grid member such that the hole in the ceramic member 22 at the lower end of grid member 21 is slightly less than the diameter of the recess in the lower end of grid member 21.

At a point somewhat below the lower end of grid member 21, for example, one diameter of the shield member 19 therebelow, the recess in ceramic member 22 is again enlarged to accommodate a cathode comprising a tubular member 23 which snugly fits in said enlarged recess, the diameter of said recess being slightly smaller than the outside diameter of grid member 21. The upper end of tubular member 23 is curved inward to form a substantially closed end, except for an aperture 24 in the center thereof, the diameter of said aperture being slightly smaller than the diameter of conducting member 13.

Inside tubular member 23 is packed electron

emissive material 25 of any desired type such as, for example, a finely divided mixture of aluminum and caesium chloride. The lower end of tubular member 25 is sealed by a metallic member 25' attached to the walls thereof as by welding. Attached to the lower end member 25 is a plurality of leads 26 which extend through the glass button 11 to provide conducting lead-in members and are of sufficient stiffness to rigidly support the cathode.

The upper end of the cathode grid assembly is rigidly positioned by a mica spacer 27 comprising a ring-like member whose inner diameter is equal to the outer diameter of grid member 21 and firmly engages said grid member. The outer diameter of mica spacer 27 is equal to the inside diameter of envelope 10 such that the outer surface of the mica spacer firmly engages the inner walls of envelope 10. The mica spacer rests on the upper end of ceramic member 22 and is rigidly urged against said ceramic member by a metallic strap 28 surrounding grid member 21 above mica spacer 27. Attached to strap 28 is a lead-in member 29 which extends downward through holes in mica spacer 27 and ceramic member 22 and through a ceramic bushing 30 positioned below insulating member 22, and thence through the sealing button 11. The upper end of the ceramic bushing 30 is accommodated by a recess in ceramic member 22 and the lower end of said bushing is firmly held to the inner surface of sealing button 11 by a ceramic glue 31.

Thus it may be seen that the mica spacer, grid, ceramic member 22 and cathode are all rigidly maintained in stacked relationship by the tension of the lead-in member 29 whereby both longitudinal and transverse movement between these elements is prevented. Since this assembly is rigidly positioned with respect to the envelope 12 by means of the spacer 27 and lead-in members 26 and ceramic sleeve 30, the relative position of this assembly to the anode assembly which is attached to the upper end of envelope 10 is maintained.

Extending transversely through ceramic member 22 and grid member 21 such that it intersects the axis of the recesses in these members is a hole 32 thereby connecting the passage between the anode and cathode with the other spaces existing in the device. When the tube fires, this central passage between the anode and cathode is heated by the discharge such that gaseous material moves outwardly through hole 32 carrying electron emissive material eroded from the cathode with it. By this action a substantial amount of electron emissive material is prevented from condensing on the grid and anode members such that the high forward and inverse voltages of the tube are not reduced as would be the case if electron emissive material were deposited on the anode and grid surfaces.

The tube may be filled with any desired gas such as, for example, helium at 12 millimeters of pressure. Also, a small quantity of water vapor may be added for the purpose of increasing operational characteristics as is more completely described in the aforementioned copending application. In operation a positive potential applied to the grid member 21 with respect to the cathode causes electrons to be attracted from the exposed upper surface of the cathode tube 23. These electrons strike gas molecules to ionize the same and create positive ions, which then fall back through the

aperture 24 to bombard the electron emissive material 25, thereby producing a supply of electrons which are attracted out through aperture 24 by the positive potential in grid 24 and which pass to the anode 17 to fire the tube.

This completes the description of the particular embodiment of the invention disclosed herein. However, many modifications thereof will be apparent to persons skilled in the art. For example, 10 different types of cathode may be used and the envelope 10 could be metallic instead of glass. Therefore, applicant does not wish to be limited to the particular details of the species described herein except as defined by the appended claims.

15 What is claimed is:

1. A gaseous discharge device comprising a cathode, an anode, a grid, and an insulating member positioned between and engaging said cathode and said grid, said cathode comprising a tubular member containing electron emissive material, a portion of the outer surface of said tubular member engaging an inner surface of a recess in said insulating member, said grid comprising a cylindrical member, the outer surface of said 20 cylindrical member engaging an inner surface of a recess in said insulating member, and means for firmly urging said cathode and said grid into said recesses.

2. A gaseous discharge device comprising a cathode, an anode, a grid, an insulating member positioned between and engaging said cathode and said grid, said cathode comprising a tubular member containing electron emissive material, the outer surface of said tubular member engaging 30 the inner surface of a recess in said insulating member, said grid comprising a cylindrical member, the outer surface of said cylindrical member engaging an inner surface of a recess in said insulating member, and means for firmly urging said cathode and said grid into said recesses comprising a base member attached to said cathode and to said grid member.

3. A gaseous discharge device comprising a cathode, an anode, a grid, an insulating member positioned between and engaging said cathode and said grid, said cathode comprising a tubular member containing electron emissive material, the outer surface of said tubular member engaging the inner surface of a recess in said insulating member whereby transverse motion between said 45 cathode and said grid is prevented, said grid comprising a cylindrical member, the outer surface of said cylindrical member engaging an inner surface of a recess in said insulating member whereby transverse motion between said grid and said insulating member is substantially prevented, and means for firmly urging said cathode and said grid into said recesses comprising a base member supportingly attached to said cathode and to said grid member.
